UNITED STATES PATENT OFFICE

JOHN E. MINTY, OF MUSKEGON, MICHIGAN, ASSIGNOR TO SHAW-CRANE-PUTNAM MACHINE COMPANY, OF MUSKEGON, MICHIGAN.

SPRING-ACTUATED REEL

Application filed October 12, 1928. Serial No. 312,066.

The main objects of this invention are:

First, to provide a spring actuated reel which is well adapted for use on cranes with lifting magnets or motor driven grab buckets or the like, and other work which might be generally designated as "heavy" work.

Second, to provide a spring winding reel in which the spring is so connected and associated with its directly coacting parts as to minimize the kinking and like strains which are likely to break the spring.

Third, to provide in a spring winding reel an improved connection for the spring which acts as a clutch or brake member when the spring is fully unwound to prevent overrunning.

Further objects will appear from the detailed description to follow. The invention is defined in the claims.

20 A structure which embodies the features of my invention is clearly illustrated in the accompanying drawing, in which:

Fig. 1 is an end elevation looking from the right of Fig. 2 with a portion of the drum broken away.

Fig. 2 is a vertical longitudinal section on a line corresponding to line 2-2 of Figs. 1, 3 and 4, the parts being shown in full lines for convenience in illustration.

30 Fig. 3 is a transverse section on line 3-3 of Fig. 2.

Fig. 4 is a transverse section on line 4-4 of Fig. 2.

Referring to the drawing, 1 represents a 35 supporting bar or bracket on which are bearing supports 2 and 3 for the shaft 4. This shaft is a non-rotating shaft except as it is rotated for adjustment, and is provided with a ratchet 5 with which the holding pawl 6 coacts. The ratchet lever 7 is provided with a pawl 8 coacting with the ratchet 5.

The drum 9 is rotatably mounted on the shaft and adapted to receive the cable, as 40. The wires of this cable are connected to the rings 11 with which the brushes 12 coact.

The details of these electrical connections, however, form no part of this invention and, therefore, are not further illustrated or described herein.

50 The structure illustrated is adapted for a

pair of actuating springs, connected in tandem relation, and while my improvements are especially adapted for structures such as illustrated, employing more than one spring, certain features thereof are equally well adapted to structures employing a single spring.

In the embodiment illustrated I provide a hub 13 which is keyed to the shaft, and a hub 14 rotatable on the shaft. Both of these hubs are provided with groove-like peripheral recesses 15 into which the segmental connectors 16 collapse when the springs are wound upon the hubs as shown in Fig. 2. These grooves are narrower than the springs so that the springs are supported by the hubs, the connections being preferably of such dimensions, however, as to complement the surface of the hubs when collapsed.

The inner ends of the springs 17 are connected to the swinging ends of these connectors 16 by means of the segmental coupling members 18 which are riveted on the inner sides of the springs and pivoted at 19 to the swinging ends of the connectors. The connectors are pivoted to the hubs by means of the pins 20.

The rotatable hub 14 is provided with a flange-like spring holder 21 which overhangs the hub 13. A corresponding annular holder 22 is connected to the drum, and in the embodiment illustrated is formed integrally with one section of the drum. This holder 22 overhangs the rotatable hub 14.

These holders are provided with segmental inwardly facing recesses 23 adapted to receive the outer connectors 24 which are pivoted at 25 to collapse into the recesses. The holders are connected to the outer ends of the springs by the rivets 26 so that when the connectors are collapsed as shown in Fig. 3 they constitute bridges for the recesses and complement the inner surface of the holders in providing a continuous support for the unwound or expanded spring.

By thus arranging the parts, I have substantially eliminated the tendency for the springs to kink in the winding and unwinding thereof, and the strain on the connections to the spring is minimized. The connectors

16 are thrown out, not only by the tension of the spring in unwinding, but also by centrifugal action, so that they engage the inner coil of the spring with a clutching action, thereby acting to prevent overrunning and kinking, or putting undue stress upon the spring and its connection.

I have illustrated and described my improvements in an embodiment which I have found highly practical. I have not attempted to illustrate or describe certain embodiments or adaptations which are possible as it is believed this disclosure will enable those skilled in the art to embody or adapt my improvements as may be desired.

Having thus described my invention what I claim as new and desire to secure by Letters Patent is:

1. In a spring actuated reel, the combination with a shaft, of a drum rotatable on said shaft, spring supporting hubs having peripheral grooves, one of said hubs being keyed to said shaft and the other being rotatable thereon, an annular spring holder on said 20 rotatable hub overhanging said fixed hub, an annular spring holder on said drum overhanging said rotatable hub overhanging said fixed hub, an annular spring holder on said drum overhanging said rotatable hub, said 25 spring holders having inwardly facing segmental recesses, springs, segmental outer connectors to which the outer ends of said springs are secured, pivoted to said holders to collapse in their said recesses, segmental 30 inner connectors pivoted to said hubs, and segmental coupling members to which the inner ends of the springs are connected pivoted to the swinging ends of said inner connectors, said inner connectors and coupling 35 members being collapsible in said grooves in said hubs so that the springs may wind 40 upon the hubs over the same.

2. In a spring actuated reel, the combination with a shaft, of a drum rotatable on said 45 shaft, spring supporting hubs having peripheral grooves, one of said hubs being keyed to said shaft and the other being rotatable thereon, an annular spring holder on said rotatable hub overhanging said fixed hub, an annular 50 spring holder on said drum overhanging said rotatable hub, said spring holders having inwardly facing segmental recesses, springs, segmental outer connectors to which the outer ends of said springs are secured 55 pivoted to said holders to collapse in their said recesses, and segmental inner connectors to which the inner ends of the springs are connected pivoted to said hubs to collapse 60 in said grooves thereof.

3. In a spring actuated reel, the combination of a shaft, a drum rotatable on said shaft, a hub having a peripheral groove therein and keyed to said shaft, an annular spring 65 holder having an inwardly facing segmental recess therein connected to said drum, a

spring, an outer segmental connector to which the outer end of said spring is connected pivoted to said holder to collapse in said recesses, an inner segmental connector pivoted to said hub, and a segmental coupling member secured to the inner end of said spring and pivoted to the outer end of said inner connector, said inner connector arm and coupling member being adapted to collapse in said groove in said hub to permit the winding of the spring upon the periphery of the hub.

4. In a spring actuated reel, the combination of a shaft, a drum rotatable on said shaft, a hub having a peripheral groove therein and keyed to said shaft, an annular spring holder having an inwardly facing segmental recess therein connected to said drum, a spring, an outer segmental connector to which the outer end of said spring is connected pivoted to said holder to collapse in said recesses, and an inner segmental connector pivoted to said hub and connected to said spring to collapse in said groove in said hub to permit the winding of the spring upon the periphery of the hub.

5. In a spring actuated reel, the combination of a shaft, a drum rotatable thereon, a hub having a peripheral groove therein and keyed to said shaft, a spring, connections for the outer end of said spring to said drum, a segmental connector pivoted to said hub, and a segmental coupling member secured to the inner end of said spring and pivoted to the outer end of said inner connector, said connector and coupling member being adapted to collapse in said groove in said hub to permit the winding of the spring upon the periphery of the hub, said inner connector having clutching engagement with said spring when the spring is unwound.

6. In a spring actuated reel, the combination of a shaft, a drum rotatable thereon, a hub having a peripheral groove therein and keyed to said shaft, a spring, connections for the outer end of said spring to said drum, a segmental connector pivoted to said hub and to said spring, said connector being adapted to collapse in said groove in said hub to permit the winding of the spring upon the periphery of the hub, said inner connector having clutching engagement with said spring when the spring is unwound.

7. In a spring actuated reel, the combination of a shaft, a drum rotatable thereon, a hub having a peripheral groove therein and keyed to said shaft, a spring, connections for the outer end of said spring to said drum, a segmental connector pivoted to said hub and to said spring, said connector being adapted to collapse in said groove in said hub to permit the winding of the spring upon the periphery of the hub and to swing out of said groove to permit the inner end of the spring

to rest in supporting engagement with the inner coil thereof.

8. In a spring actuated reel, the combination of a shaft, a drum rotatable thereon, a hub on said shaft, a spring, connections for the outer end of said spring to said drum, and a connector pivotally connected to said hub to collapse therein and connected to the inner end of said spring, said connector being of such length as to permit it to swing into frictional engagement with the inner coil of said spring when it is unwound.

9. In a spring actuated reel, the combination of a shaft, a drum rotatable thereon, a spring, connections for the outer end of said spring to said drum, and a segmental connector pivotally connected to said shaft and pivotally connected to the inner end of said spring, said connector being of such length as to permit it to swing into frictional engagement with the inner coil of said spring when it is unwound.

10. In a spring actuated reel, the combination of a shaft, a drum rotatable thereon, a spring, connections for the outer end of said spring to said drum, and a connector pivotally connected to said shaft and connected to the inner end of said spring, said connector being of such length as to permit it to swing into frictional engagement with the inner coil of said spring when it is unwound.

11. In a spring actuated reel, the combination of a shaft, a drum rotatable thereon, an annular spring holder having a segmental recess therein and connected to said drum, a spring, connections for the inner end of said spring to said shaft, and a segmental connector to which the outer end of said spring is connected pivoted to said holder to collapse in said recess thereof and when collapsed to constitute a bridge member for said recess.

12. In a spring actuated reel, the combination of a shaft, a drum rotatable thereon, a spring, connections for said spring to the inner end of said shaft, a spring holder connected to said drum, and a segmental connection for the outer end of said spring to the holder pivoted to the holder to collapse therein and when collapsed complementing the annular spring supporting surface of the holder.

13. In a spring actuated reel, the combination of a shaft, a drum rotatable relatively to said shaft, a hub connected to said shaft, a spring surrounding said hub, an annular spring holder connected to said drum and having an inner cylindrical surface against which the spring expands when unwound and a recess in said inner surface, a arcuately shaped connector pivotally mounted at one end on said holder in said recess and having its free end secured to the outer end of the spring, said connector being arranged to collapse into said recess when the spring is un-

wound so that the outer coil of the spring expands uniformly against the holder, and means to connect the inner end of the spring to the hub.

14. In a spring actuated reel, the combination of a shaft, a drum rotatable on said shaft, a hub connected to said shaft and provided with a recess therein, a spring surrounding said hub, means to connect the outer end of said spring to said drum, a coupling member secured to the inner end of said spring, a connector having one end pivotally mounted on said hub and its other end pivotally connected to said coupling, said connector and coupling being arranged to collapse into the recess in the hub when the spring is wound, said connector having a laterally projecting portion so that when the spring is unwound, the projecting portion engages the inner coil of the spring and prevents over-running.

15. In a spring actuated device, the combination of a shaft, a hub connected to said shaft, a spring surrounding said hub, means connecting the inner end of said spring to said hub permitting the spring to be wound tightly on the hub or unwound therefrom without subjecting the end of the spring to kinking strains, an annular member rotatable relatively to said shaft and having an inner cylindrical surface against which the spring expands when unwound and means connecting the outer end of the spring to said member permitting the spring to be wound or unwound without subjecting the end thereof to any kinking strains.

16. In a spring actuated device, the combination of a shaft, a hub on said shaft, a spring surrounding said hub, means connecting the inner end of said spring to said hub permitting the spring to be wound tightly on the hub or unwound therefrom without subjecting the end of the spring to kinking strains, an annular member rotatable relatively to said shaft and having an inner cylindrical surface against which the spring expands when unwound and means connecting the outer end of the spring to said member.

17. In a spring actuated device, the combination of a shaft, a hub on said shaft, a spring surrounding said hub, means connecting the inner end of said spring to said hub, an annular member rotatable relatively to said shaft and having an inner cylindrical surface against which the spring expands when unwound and means connecting the outer end of the spring to said member permitting the spring to be wound or unwound without subjecting the end thereof to any kinking strains.

In witness whereof I have hereunto set my hand.

JOHN E. MINTY.
